UNITED STATES PATENT OFFICE.

LYMAN A. WHEAT, OF BATTLE CREEK, MICHIGAN, has invented new and useful Improvements in Printing-Presses,

PRINTING-PRESS.

No. 926,795. Patented July 6, 1909.

Application filed January 2, 1908. Serial No. 408,997.

To all whom it may concern:

Be it known that I, LYMAN A. WHEAT, a citizen of the United States, residing at the city of Battle Creek, county of Calhoun, State of Michigan, have invented certain new and useful Improvements in Printing-Presses, of which the following is a specification.

This invention relates to improvements in rotary printing presses.

10 The objects of the invention are,—first, to simplify the construction of such rotary printing presses, making them compact and efficient; Second, to provide a construction of rotary printing presses where all of the 15 rolls are readily and completely accessible in use, and, further, so constructed that the said rolls can be readily removed and replaced; Third, to provide an arrangement and construction of rollers in such a rotary 20 press that will deliver the web without material turn in its direction, and the impression points for the opposite sides shall be in close proximity to avoid displacement of the paper by stretching.

25 Further objects and objects pertaining to mere details of construction will fully appear from the detailed description to follow.

I accomplish the objects of my invention by the devices and means described in the 30 following specification.

The invention is clearly defined and pointed out in the claims.

A structure embodying the features of my invention is fully illustrated in the accompanying drawing, forming a part of this specification, in which—

Figure 1 is an end elevation of my improved rotary press, portions thereof and their relation to each other being indicated 40 by dotted lines. Fig. 2 is a side elevation of the same with the ink rolls and their supports entirely omitted. Fig. 3 is a transverse detail sectional view taken on a line corresponding to line 3—3 of Fig. 2, with the inking 45 rolls in position, looking toward the right, as indicated by the little arrows. Fig. 4 is a detail sectional view of the machine through the upper part of the left-hand frame end of Fig. 2, taken on the line corresponding to line 50 4—4 of Fig. 2, looking toward the left, as indicated by the little arrows.

In the drawing similar numerals of reference refer to similar parts throughout the several views.

55 Considering the numbered parts of the drawing, the frame consists of suitable heavy

cast frame-like ends 1 and 2, which extend down and form part of the base. These ends are arch-shaped and open at the center. These ends are coupled together by longitudinal base bars 3, which serve also the purpose of ink fountains, being made into troughs for that purpose, and are each provided with longitudinal rolls 3', 3', supported in any usual and well-known way therein.

60 A yoke 4 is secured to the end piece 1 by suitable means, and serves to support the tight and loose pulleys 6 which are carried on a suitable shaft 6' supported in suitable journal boxings 6'', and these serve to drive the 70 machine by the gear 7, which is on the said shaft 6'.

The impression cylinder 8 is supported on the shaft 8' which rests in suitable journal boxes 8'', which are on cross arms 1' and 2' 75 at each end, which are detachably secured within the arch of the frame-like ends 1 and 2 respectively. The opening in the frame ends is of such dimensions that by detaching the cross arms 1' and 2', the said impression 80 cylinder 8 may be readily withdrawn. All the other cylinders or rolls necessary to make up the press are supported in suitable capped journal boxings on the outside edge of the said arched end pieces 1 and 2, and can thus 85 readily be removed by simply removing the caps of the said journal boxes.

The type cylinder 9 corresponding to and coöperating with the impression cylinder 8 to form the lower printing couple is supported 90 at a point above and in front of the said impression cylinder 8, and overhangs the same at the front of the machine to a considerable extent. This type cylinder 9 is carried on the shaft 9' which is supported in suitable 95 capped boxes 9'', eccentric bushing 9''' being placed on the shaft to facilitate the adjustment of the same.

The impression cylinder 10 for printing the opposite side of the web is supported at the 100 top of the machine ends on the outside of the arches in suitable journal bearings 10'', an eccentric bushing 10''' being provided for the adjustment thereof. The type cylinder 11 corresponding to the upper impression 105 cylinder 10 to form the upper printing couple is supported at the rear of the machine and overhangs the impression cylinder 8 to the rear, and projects rearwardly from a position at the rear of the frame, which corresponds 110 exactly to the position of the impression cylinder 9 at the front. The said type cylinder

11 is supported on the shaft 11' in suitable capped boxes 11'', which boxes are provided with eccentric bushing 11''' at the rear of the said machine. It will be seen that so far as 5 the type cylinders are concerned that there is a symmetrical arrangement of the same in the frame of the printing press.

The various cylinders are provided with and are driven by corresponding gears, the 10 cylinder 8 being driven by the gear 8'' on its shaft 8', the type cylinder 9 being driven by the gear 9'' on its shaft 9', the impression cylinder 10 being driven by the gear 10'' on its shaft 10', and the type cylinder 11 being 15 driven by the gear 11'' on its shaft 11'.

The gear wheels 8'' and 9'' mesh together, as do the gear wheels 10'' and 11'', and an intermediate gear 12'' is provided between the 20 gears 8'' and 11'', it being supported on a journal pin 12' on the frame 1, so that the said cylinders in pairs feed in the same direction, and owing to their arrangement it will be noticed that each pair of cylinders, consisting of an impression cylinder and a type 25 cylinder, are in juxtaposition to each other. The impression cylinders are arranged above and below, and the type cylinders overhang the lower impression cylinder, so that the inking rollers and apparatus can be arranged 30 beneath the said type cylinders, both front and back, permitting ready access to the said cylinders for the purpose of applying stereotype or electrotype plates thereto, and also affording ready access to the inking apparatus 35 and all other parts of the machine. It will be noted that this arrangement also permits ready access to the central and lower impression cylinders from a pit beneath the machine, which makes it very convenient for 40 applying the blankets or other cushioning material thereto.

The ink drums 16, 16 are supported on suitable shafts 16' held in place by capped boxings 16'' at each side. Distributer rolls 45 18 are placed on the under side of the said ink drums 16, being supported in any well known way not here illustrated, such illustration not being deemed necessary.

Ink rolls 17 are provided, arranged, 50 constructed and operated to coöperate with the fountains and their rolls in any well known way. A pair of ductor rolls 19 are provided at each side to deliver the ink from the ink drum 16 to the type cylinders, these being 55 supported in any well known and usual way. As this invention does not pertain to the details of or the mechanism of these inking rolls and apparatus, and as it is purposed to employ the usual construction of rolls, it is 60 deemed only necessary to illustrate the position in which the rolls are arranged and supported in my improved rotary press. I show the preferred arrangement. I am aware that other arrangements of ink rolls 65 and apparatus might be devised and adopt-

ed, but the particular arrangement of impression and type cylinders of my improved press makes this arrangement of rolls practical, convenient and very compact, and it is the form and arrangement which I wish to 70 claim specifically.

On the top of the frame ends 1 and 2 are provided upwardly extending brackets 5—5 which bear the delivery roll 13' over which the web of paper 15 is discharged from the 75 press, and passes to a suitable folder, or to an angle bar and thence to a suitable folder, these being common devices and not here illustrated. A guide roll 13 is provided on the bottom of the machine over which the 80 web 15 passes to the press from the paper roll 14, which is preferably arranged beneath the floor. The direction of the web 15 clearly appears in Figs. 1 and 3, the same passing to the guide roll 13 in the base of the machine, 85 thence upward into contact with the impression cylinder 8, thence between it and the type cylinder 9, thence directly onward and upward between the impression cylinder 10 and the type cylinder 11, where the opposite side of the sheet is printed, then out at 90 the top over the delivery roll 13'.

I desire to remark that in my improved press, while utilizing type cylinders of the usual size and impression cylinders of the 95 usual size and sufficiently large for the purpose, I am able to produce a machine which is only between three and four feet high; where the type cylinders are perfectly accessible for the handling and applying of the 100 heavy stereotype plates; in which every part of the machine is conveniently accessible; which can be readily taken apart for repairs and can be readily adjusted, saving greatly 105 in the time and labor necessary to properly operate the same.

While I have shown the structure in the preferred form, variations and modifications will no doubt occur to those skilled in the art to which this invention pertains, and no 110 doubt the supporting frame work could be arranged at various angles with the rolls supported in the relations that I have indicated, and suitable inking means could be provided for inking the type cylinders, but it will be 115 observed that the exact arrangement that I have shown makes it possible to form the ink fountains to be arranged in the base, and that all the parts are arranged very compactly.

I desire to be understood that I wish to 120 claim the particular embodiment of my invention very specifically and also that I wish to claim the improvements that I have produced broadly, as they might be utilized in various forms and ways.

Having thus described my invention, what I desire to claim, is:

1. In a rotary printing press, the combination of the frame-work made up of arch shaped ends, 1 and 2; base bars 3 having ink 130

fountains formed in their upper surfaces, connecting said arch-shaped ends; removable cross bars 1' and 2' within the said arches, having suitable journal bearings thereon; an impression cylinder 8, the journals of which are supported on the said cross bars, being of such dimensions as to be removable through the openings of the said arch-shaped ends; a type cylinder 9 corresponding to the impression cylinder 8, supported on a suitable shaft, which is supported in suitable adjustable capped boxings on the front of the said arch-shaped end portions and overhanging the said impression cylinder; an impression cylinder 10 on a shaft 10' supported in capped boxings on the top of the said arched frame; a type cylinder 11 corresponding to the impression cylinder 10 supported on a shaft in adjustable capped boxings to the rear of the frame of the said machine and overhanging the said impression cylinder 8; ink drums arranged beneath the said type cylinders at front and rear, whereby the said type cylinders are exposed and readily accessible; suitable distributor and ductor rolls for passing the ink from the said fountains to the said type cylinders; suitable gearings for driving the said cylinders; a guide roll 13 for the web in the lower part of said frame arranged to guide the web and deliver it upwardly into contact with the impression cylinder 8, thence between it and the type cylinder 9, thence between the impression cylinder 10 and its corresponding type cylinder 11, and a delivery roll 13' at the top of the machine, as described.

2. In a rotary printing press, the combination of the frame-work made up of arch-shaped ends, 1 and 2; base bars 3 having ink fountains formed in their upper surfaces, connecting said arch-shaped ends; removable cross bars 1' and 2' within the said arches, having suitable journal bearings thereon; an impression cylinder 8, the journals of which are supported on the said cross bars, being of such dimensions as to be removable through the openings of the said arch-shaped frame ends; a type cylinder 9 corresponding to the impression cylinder 8, supported on a suitable shaft, which is supported in capped boxings on the front of the said arch-shaped end portions and overhanging the said impression cylinder; an impression cylinder 10 on shaft 10' supported in capped boxings on the top of the said arched frame; a type cylinder 11 corresponding to the impression cylinder 10 supported on a shaft in capped boxings to the rear of the frame of the said machine and overhanging the said impression cylinder 8; ink drums arranged beneath said type cylinders at front and rear, whereby the said type cylinders are exposed and readily accessible; suitable distributor and ductor rolls for passing the ink from the said fountains to the said type cylinders; suitable gearings for driving the

the said cylinders; a guide roll 13 for the web in the lower part of said frame arranged to guide the web and deliver it upwardly into contact with the impression cylinder 8, thence between it and the type cylinder 9, thence between the impression cylinder 10 and its corresponding type cylinder 11, and a delivery roll 13' at the top of the machine, as described.

3. In a rotary printing press, the combination of the frame-work made up of arch-shaped ends, 1 and 2; base bars 3 having ink fountains formed in their upper surfaces, connecting said arch-shaped ends; removable cross bars 1' and 2' within the said arches, having suitable journal bearings thereon; an impression cylinder 8, the journals of which are supported on the said cross bars, being of such dimensions as to be removable through the openings of the said arch-shaped frame ends; a type cylinder 9 corresponding to the impression cylinder 8, supported on a suitable shaft, which is supported in boxings in the front of the said arch-shaped end portions and overhanging the said impression cylinder; an impression cylinder 10 on a shaft 10' supported in capped boxings on the top of the said arched frame; a type cylinder 11 corresponding to the impression cylinder 10 supported on a shaft in boxings to the rear of the frame of the said machine and overhanging the said impression cylinder 8; ink drums arranged beneath the said type cylinders at front and rear, whereby the said type cylinders are exposed and readily accessible; suitable distributor and ductor rolls for passing the ink from the said fountains to the said type cylinders; suitable gearings for driving the said cylinders; a guide roll 13 for the web in the lower part of said frame arranged to guide the web and deliver it upwardly into contact with the impression cylinder 8, thence between it and the type cylinder 9, thence between the impression cylinder 10 and its corresponding type cylinder 11, and a delivery roll 13' at the top of the machine, as described.

4. In a rotary printing press, the combination of the frame-work made up of arch-shaped ends, 1 and 2; base bars 3, connecting said arch-shaped ends; removable cross bars 1' and 2' within the said arches, having suitable journal bearings thereon; an impression cylinder 8, the journals of which are supported on the said cross bars, being of such dimensions as to be removable through the openings of the said arch-shaped frame ends; a type cylinder 9 corresponding to the impression cylinder 8, supported on a suitable shaft, which is supported in boxings on the front of the said arch-shaped frame end portions and overhanging the said impression cylinder; an impression cylinder 10 on shaft 10' supported in capped boxings on the

top of the said arched frame; a type cylinder 11 corresponding to the impression cylinder 10 supported on a shaft 11' in boxings to the rear of the frame of the said machine and 5 overhanging the said impression cylinder 8; ink drums and apparatus arranged beneath the said type cylinders at front and rear, whereby the said type cylinders are exposed and readily accessible; suitable gearings for 10 driving the said cylinders; a guide roll 13 for the web in the lower part of said frame arranged to guide the web and deliver it upwardly into contact with the impression cylinder 8, thence between it and the type 15 cylinder 9, thence between the impression cylinder 10 and its corresponding type cylinder 11, and a delivery roll 13' at the top of the machine, as described.

5. In a rotary printing press, the combination of the frame-work, made up of arch-shaped ends with base bars connecting the bottoms thereof; an impression cylinder supported on suitable bearings within the said frame and of such dimensions as to be 20 removable through the arch-shaped ends; a type-cylinder corresponding to said impression cylinder, forming a printing couple; and a second printing couple consisting of an impression cylinder and a type cylinder supported on suitable shafts arranged in suitable capped boxings on the outside of the 25 said arch-shaped ends; and adjustable eccentric bushings on at least the shaft of one roll of each couple arranged within the said capped boxings for the adjustment of the 30 said rolls in their relations to each other, co-acting for the purpose specified.

6. In a rotary printing press, the combination of the frame-work, made up of arch-shaped ends with base bars connecting the bottoms thereof; an impression cylinder supported on suitable bearings within the said frame and of such dimensions as to be removable through the arch-shaped ends; a 40 type cylinder corresponding to said impression cylinder, forming a printing couple, and a second printing couple consisting of an impression cylinder and a type cylinder supported on suitable shafts arranged in suitable capped boxings on the outside of the 45 said arch-shaped ends; coacting for the purpose specified.

7. In a rotary printing press, the combination of a suitable frame; an impression cylinder in the lower portion thereof; a corresponding type cylinder arranged above and in front thereof and overhanging the same, and geared to coöperate therewith; an impression cylinder in the upper part of the 55 machine; a type cylinder corresponding to the said upper impression cylinder and geared to coöperate therewith, arranged to the rear of the said frame and overhanging the lower impression cylinder toward the 60 rear; intermediate gear for driving the said 65 rear; intermediate gear for driving the said

pairs of cylinders together; suitable means for driving the said cylinders; capped journal boxings for the journals of said cylinders; suitable inking apparatus arranged beneath the said type cylinders at front and rear; a suitable ink fountain formed in the base of the said frame at the front and rear side; a suitable guiding roll in the bottom of said press for delivering a web of paper to the said impression and type cylinders; and a 70 roll for delivering the web of paper from the top of the machine, coacting for the purpose specified.

8. In a rotary printing press, the combination of a suitable frame; an impression cylinder in the lower portion thereof; a corresponding type cylinder arranged above and in front thereof and overhanging the same and geared to coöperate therewith; an impression cylinder in the upper part of the machine; a type cylinder corresponding to the said upper impression cylinder and geared to coöperate therewith, arranged to the rear of the said frame and overhanging the lower impression cylinder toward the rear; intermediate gear for driving the said pairs of cylinders together; suitable means for driving the said cylinders; suitable inking apparatus arranged beneath the said type cylinders at front and rear; a suitable ink fountain formed in the base of the said frame at the front and rear side; a suitable guiding roll in the bottom of said press for delivering a web of paper to the said impression and type cylinders; and a roll for delivering the 80 web of paper from the top of the machine, coacting for the purpose specified.

9. In a rotary printing press, the combination of a suitable frame; an impression cylinder in the lower portion thereof; a corresponding type cylinder arranged above and in front thereof and overhanging the same and geared to coöperate therewith; an impression cylinder in the upper part of the machine; a type cylinder corresponding to the said upper impression cylinder and geared to coöperate therewith, arranged to the rear of the said frame and overhanging the lower impression cylinder, toward the rear; intermediate gear for driving the said pairs of cylinders together; suitable means for driving the said cylinders; suitable inking apparatus arranged beneath the said type cylinders at front and rear; a suitable guiding roll in the bottom of said press for delivering a web of paper to the said impression and type cylinders; and a roll for delivering the web of paper from the top of the machine, coacting for the purpose specified.

10. In a rotary printing press, the combination of a suitable frame; an impression cylinder in the lower portion thereof; a corresponding type cylinder arranged above and in front thereof and overhanging the same and geared to coöperate therewith; an im-

- pression cylinder in the upper part of the machine; a type cylinder corresponding to the said upper impression cylinder and geared to coöperate therewith, arranged to the rear of 5 the said frame and overhanging the lower impression cylinder toward the rear; intermediate gear for driving the said pairs of cylinders together; suitable means for driving the said cylinders; capped journal boxings for 10 the journals of said cylinders; suitable inking apparatus for the said type cylinders at front and rear; a suitable ink fountain formed in the base of the said frame at the front and rear side; a suitable guiding roll in the bot- 15 tom of said press for delivering a web of paper to the said impression and type cylinders; and a roll for delivering the web of paper from the top of the machine, coacting for the purpose specified.
- 20 11. In a rotary printing press, the combination of a suitable frame; an impression cylinder in the lower portion thereof; a corresponding type cylinder arranged above and in front thereof and overhanging the same 25 and geared to coöperate therewith; an impression cylinder in the upper part of the machine; a type cylinder corresponding to the said upper impression cylinder and geared to coöperate therewith, arranged to the rear of 30 the said frame and overhanging the lower impression cylinder toward the rear; intermediate gear for driving the said pairs of cylinders together; suitable means for driving the said cylinders; suitable inking apparatus 35 for the said type cylinders at front and rear; a suitable ink fountain formed in the base of the said frame at the front and rear side; a suitable guiding roll in the bottom of the said press for delivering a web of paper to the said 40 impression and type cylinders; and a roll for delivering a web of paper from the top of the machine, coacting for the purpose specified.
12. In a rotary printing press, the combination of a suitable frame; a lower printing 45 couple consisting of an impression cylinder in the lower portion thereof and a corresponding type cylinder arranged above and in front thereof and overhanging the same and geared to coöperate therewith; an upper printing couple consisting of an impression cylinder in 50 the upper part of the machine arranged substantially above the lower impression cylinder and in proximity thereto, and a type cylinder corresponding thereto and geared to coöperate therewith, arranged to the rear of 55 the said frame, the said upper type cylinder overhanging the lower impression cylinder toward the rear and in proximity thereto, whereby the said type cylinders of both printing couples are readily accessible; suitable 60 means for driving the said cylinders; suitable inking apparatus for the said type cylinders at front and rear beneath said type cylinders; a suitable guiding roll in the bottom of said press for delivering a web of paper to the said impression and type cylinders; and a roll for delivering the web of paper from the top of the machine, coacting for 65 the purpose specified.
13. In a rotary printing press the combination of a suitable frame; type cylinders symmetrically arranged toward the front and rear thereof and projecting outwardly from the said framework whereby their surfaces are exposed and made accessible; impression 70 cylinders corresponding to the said type cylinders and coacting therewith to form printing couples, said impression cylinders being arranged toward the interior of said press at different elevations and in juxtaposition one 75 above and the other below the level of the corresponding type cylinder whereby a compact structure is obtained; and inking apparatus arranged below the said type cylinders to deliver ink thereto; and a guide below the 80 said frame for a web of paper to deliver the web beneath the frame of said press and thence upwardly therethrough, coacting as 85 specified.
- In witness whereof, I have hereunto set 90 my hand and seal in the presence of two witnesses.
